UNITED STATES PATENT OFFICE.

WALLACE CHARLES YEOMANS, OF PE ELL, WASHINGTON.

MANUFACTURE OF CRATES.

No. 883,070.

Specification of Letters Patent. Patented March 24, 1908.

Application filed January 22, 1907. Serial No. 353,441.

To all whom it may concern:

Be it known that I, WALLACE CHARLES YEOMANS, a citizen of the United States, and a resident of Pe Ell, in the county of Lewis 5 and State of Washington, have invented new and useful Improvements in the Manufacture of Crates, of which the following is a full, clear, and exact description.

The object of the invention is to provide 10 certain new and useful improvements in the manufacture of crates, whereby the blank for forming the crate is woven flat in single piece, and the connected parts of the blank thus produced can be readily folded and 15 closed to form a complete crate without requiring extra fastening devices.

The invention consists of novel features and parts and combinations of the same, which will be more fully described hereinafter 20 and then pointed out in the claims.

A practical embodiment of the invention is represented in the accompanying drawings forming a part of this specification, in which similar characters of reference indicate corre- 25 sponding parts in all the views.

Figure 1 is the plan view of the blank for forming the crate; Fig. 2 is a perspective view of the complete crate, and Fig. 3 is an enlarged side elevation of a portion of the 30 closing corner of the crate.

The crate is formed from a single blank made of slats wired together, as hereinafter more fully described, and the said single blank in its entirety and as shown in Fig. 1 35 consists of a back A, a bottom B extending from the front end of the back A, a top C extending from the rear end of the back A, a side D extending from the left-hand side of the back A, a side E extending from the 40 right-hand side of the back A, and a front F extending from the outer end of the side E.

The several parts A, B, C, D, E and F of the crate are formed of spaced slats A', B', C', D', E' and F', respectively, of which the 45 outer ends A', B', C' and the inner ends of the slats D', E' are wired together by the binding wires G and G', and one or more intermediate binding wires G² engage the slats A', B', C', as indicated in the drawings. The 50 slats A', D' and A', E' alternate at their adjacent ends, and the outer ends of the slats D' are connected with each other by binding wires G³, and a similar binding wire G⁴ engages the outer ends of the slats E' and the

inner ends of the slats F', the latter alternating with the slats E'.

Now in order to fold or set up the crate, the sides D and E are swung upwardly into right angled positions relative to the back A, and then the front F is swung downwardly 60 into a right angled position relative to the sides D and E, and the free ends of the slats F' are passed into the loops formed by the binding wires G³ between the adjacent slats D', and then the rectangular frame thus formed 65 is swung up into a right angled position relative to the bottom B, after which the top C is swung down to close the crate. Now the ends of the binding wire G² are preferably extended, as at G⁵ and G⁶, to permit of looping these 70 ends G⁵, G⁶ onto the adjacent front slats F' so as to securely close the crate, as indicated in Fig. 2. In addition staples H may be driven into the free ends of the slats F' at the loops of the binding wires G³ so as to prevent the 75 front slats F' from accidentally slipping out of the said loops.

It is understood that any additional binding wires may be used on any one of the parts of the blank, so as to give the desired strength 80 to the crate according to the intended use thereof.

Now by the arrangement, the blanks when in a flat state can be readily packed, one on top of the other, and conveniently shipped 85 from the manufacturer to the consumer in a comparatively small space, thus reducing the expense of transportation to a minimum. It will also be seen that the user can readily set up the blank to form the crate, and to fill 90 and close the same securely, and the receiver of the filled crate after emptying the contents can re-ship the crate in a flat condition, to allow re-use thereof as often as desired.

Having thus described my invention, I 95 claim as new and desire to secure by Letters Patent:

A crate of the class described composed of spaced slats wired together, and comprising a back, a bottom and a top, the slats comprising which parts are arranged parallel with each other and secured together by end wires and intermediate wires, ends the slats of which are interposed between the ends of the slats of the back and secured in place by the 100 end wires of said back, the outer ends of said ends being wired together, and a front the slats of which are interposed between the 105

outer ends of the slats of one of the ends, the other ends of said slats being adapted to be interposed between the outer ends of the slats of the other end, the intermediate wires 5 of the back, top and bottom being extended, for securing the top and bottom to the front when the crate is set up.

In testimony whereof I have signed my name to this specification in the presence of two subscribing witnesses.

WALLACE CHARLES YEOMANS.
